CLAIM

The ornamental design for a combined holder-server tray and cooking pan, as shown and described.

DESCRIPTION

FIG. 1 is a top perspective view of a combined holder-server tray and cooking pan showing my new design; FIG. 2 is an exploded elevational view thereof as seen from the front or rear of FIG. 1;

FIG. 3 is an exploded elevational view thereof as seen from the left or right end of FIG. 1;

FIG. 4 is a sectional view thereof taken on line 4—4 of FIG. 1;

FIG. 5 is a plan view of the holder-server tray of FIG. 1 in an inverted condition with a cooking pan of smaller proportions nested therein;

FIG. 6 is an elevational view of the design of FIG. 5 as seen from the front or rear thereof; and

FIG. 7 is a sectional view of the design of FIG. 5 taken on line 7—7 of FIG. 5.

FIG. 5

FIG. 6

FIG. 7
